[57] CLAIM

The ornamental design for a sundial medallion, substantially as shown and described.

DESCRIPTION

FIG. 1, is a face view of a sundial medallion showing my new design in the wristband supported form;
FIG. 2, is a left side elevational view thereof;
FIG. 3, is a face view of a sundial medallion showing a modified form of my new design in the neck chain supported pendant form; and
FIG. 4, is a left side elevational view thereof.
The back is plain in both forms.
